UNITED STATES PATENT OFFICE.

OTTO W. LITZENBERG, OF NEW YORK, N. Y., ASSIGNOR TO COLUMBIA WOOD TOOL COMPANY INC., OF NEW YORK, N. Y., A CORPORATION OF NEW YORK.

TOY.

1,325,098.

Specification of Letters Patent.

Patented Dec. 16, 1919.

Application filed March 12, 1919. Serial No. 282,134.

To all whom it may concern:

Be it known that I, OTTO W. LITZENBERG, a citizen of Germany, and resident of the borough and county of the Bronx, city and State of New York, have invented certain new and useful Improvements in Toys, of which the following is a specification.

My invention relates to toys and has for its object the provision of a rocking toy which, in addition to its rocking movements, is capable also of traveling over a surface.

The particular object of my invention is to provide an improved construction of maximum efficiency and simplicity and in which the element of safety is maintained at a very high degree. Other more specific objects of my invention will appear from the description hereinafter and the features of novelty will be pointed out in the appended claims.

In the accompanying drawings, which show an example of my improved toy, Figure 1 is a side elevation; Fig. 2 is an end view; Fig. 3 is a sectional view on the line 3—3 of Fig. 1; Fig. 4 is a plan view; Figs. 5 and 6 are side elevations illustrating different positions of the toy in use; and Fig. 7 is a horizontal section on the line 7—7 of Fig. 3.

As illustrated in the drawings, the toy comprises front rockers 10 and rear rockers 11 connected together respectively, by means of cross-bars 12 and 13, and 14 and 15; in their normal positions, the front and rear rockers overlap each other at their opposed portions, the illustration showing the front rockers 10 projecting within the rear rockers 11 and having their inner free ends provided with cushions 16 of felt or the like, for engagement with the cross-bar 14, as shown in Fig. 7.

The front rockers 10 carry a front section consisting of an upright 17 secured to and extending upwardly from the cross-bar 13 and an inclined brace 18 having its one end fastened to the upright 17 and its other end secured to the cross-bar 12. The front section includes further a seat or saddle 19 carried by the upright 17 and preferably having a back 20; a pair of rigid members 21 are secured to and depend from the saddle 19 at opposite sides and are provided with a series of apertures 22 for the accommodation of a foot-bar 23. The latter, which projects equally in opposite directions from said members 21, may be held in posi-

tion in the apertures 22 simply by friction, or, as shown, cotter-pins 24 may be utilized for this purpose. In addition, a member 25 extends upwardly from the inclined brace 18 and is provided with handles 26 within easy reach of the saddle 19 and which may be readily grasped by the child when operating the toy; by fashioning the member 25 in the form of a horse's head and neck, as shown, or otherwise, as may be desired, the attractiveness of the toy is enhanced without adding any complications thereto.

The rear rockers 11 carry a rear section complementary to the front section and similarly comprising an upright 27 secured to and extending up from the cross-bar 14 and an inclined brace 28 having its one end connected with said upright 27 and its other end secured to the cross-bar 15. The upper end of the upright 27 is thickened either by properly shaping the upright itself or by securing a block 29 thereto as shown, and is pivotally connected at this end, by means of a hinge 30, with the upright 17 as shown in Figs. 5 and 6. The upper end of the upright 27 is beveled or inclined as indicated at 31 and is preferably provided with a cushion of felt or other suitable material 32 for engagement with the lower surface of the saddle 19; in addition, a stop 33, preferably of yielding material, is secured to the brace 28. The inclined surface 31 and its cushion 32 and the stop 33, coöperate with the saddle 19 to limit the pivotal forward movement of the front section for the purpose to be more fully described hereinafter; it will be understood that either the inclined surface 31 or the stop 33 may be omitted in which case the remaining element alone will serve to arrest the pivotal forward movement of said front section in the desired manner.

In its normal position the toy is in a state of equilibrium as indicated in Fig. 1; in using the toy the child straddles the same and sits upon the saddle 19 with his feet resting upon the projecting end portions of the foot-bar 23, which may be adjusted to different distances from the saddle 19 to suit the child in question by being placed in the different apertures 22.

If the toy is now rocked backward, it will finally rest upon the rear rockers 11, thus removing the front rockers 10, substantially throughout their length, from engagement

with the surface upon which the toy rests. As soon as this happens, the weight of the child on the saddle 19 will swing the front section on the hinge 30 to the position indicated in Fig. 5; in other words, said forward rockers 10 will assume a position advanced with respect to the normal position shown in Fig. 1. The described forward swinging of the front rockers 10 may be facilitated 10 by the child throwing his weight backward on the saddle 19 and pushing forwardly on the foot-bar 23.

In any case, the forward swinging movement of the front rockers 10 is arrested when 15 the saddle 19 comes into contact with the cushion 32 of the inclined surface 31 and the stop 33 or with either of them. It will be understood that the inclination of the surface 31 and the location and dimensions of 20 the stop 33 are predetermined in accordance with the extent of forward swing it is intended to give to the front rockers 10.

The toy, in rocking forwardly, is finally supported upon the front rockers 10 in their 25 advanced position and is thus advanced from its previous location; as the toy is thus rocked forwardly, the rear rockers 11 will be removed from engagement with the surface previously mentioned, as indicated by 30 dotted lines in Fig. 6. As soon as this happens, said rear rockers 11 will swing forwardly by gravity from the position shown by dotted lines in Fig. 6 until the cross-bar 14 contacts with the cushions 16 on the ends 35 of the front rockers 10 or, in other words, until the position shown in full lines in Fig. 6 is reached. The rear rockers 11 have thus again resumed their normal position relative to the front rockers which are again swung 40 forwardly in the manner previously described, as the toy again rocks backwardly.

Thus, each time the toy is rocked backwardly, the forward rockers 10 are swung to a new advanced position from which it follows that the toy, in rocking forwardly upon 45 said front rockers 10, assumes a new position, advanced with respect to its previous position. The toy thus not only describes rocking movements but is caused to travel 50 over the surface upon which it rests.

If it is desired to use the toy simply as a rocking toy, the two sets of rockers 10 and 11 may be detachably locked together in any suitable manner against relative movement; 55 for instance, hooks 34 pivotally attached to the cross-bar 14 and hooking into eyelets 35 secured upon the cross-bar 13, may be provided for this purpose, as shown in Fig. 7.

In addition, the rear rockers 11 may be provided with suitably located stops 36 whereby 60 the backward rocking of the toy is arrested within limits which are safe and whereby overturning is prevented.

By providing the depending members 21 and foot rests 23 and rigidly connecting 65 them with the saddle 19, the child is given a maximum of control over the toy in all positions and is not likely to be accidentally dislodged therefrom; further, the manipulation of the toy is facilitated and brought 70 under the positive control of the rider. The danger of accidents is thus reduced to a minimum.

The toy is simple in construction with all parts readily accessible and may be produced 75 at a low cost, is positive in action, and operates smoothly and efficiently without jars or shocks.

Various changes in the specific form shown and described may be made within 80 the scope of the claims without departing from the spirit of my invention.

I claim:

1. A toy of the kind described comprising complementary front and rear sections including front and rear rockers, said sections being pivotally connected together, a saddle on the front section arranged to be depressed under the weight of the rider whereby said front section and its rockers are swung forwardly relatively to said rear section, and means on said rear section whereby the relative swinging of said front section is arrested. 85

2. A traveling rocking toy comprising 95 front rockers, rear rockers, front and rear frames carried respectively by said front and rear rockers and converging upwardly, said frames being pivotally connected at their upper ends, a saddle carried by said front frame whereby the latter and the front rockers are pivotally swung relatively to the rear frame and rocks under the weight of the rider, stopping means on said rear frame co-operating with said saddle to arrest 100 the relative pivotal movement of said front frame, rigid members fixed upon and depending from said saddle and each provided with a series of apertures, a foot-bar arranged to fit said apertures, a member carried by said front section and rigid handles fixed upon said last named member. 105

In testimony whereof I have hereunto set my hand.

OTTO W. LITZENBERG.
